UNITED STATES PATENT OFFICE.

ALONZO E. RHOADES, OF HOPEDALE, MASSACHUSETTS, ASSIGNOR, BY MESNE ASSIGNMENTS, TO DRAPER CORPORATION, OF HOPEDALE, MASSACHUSETTS, A CORPORATION OF MAINE,
FEELER-MOTION FOR LOOMS.

1,262,565.

Specification of Letters Patent.

Patented Apr. 9, 1918.

Application filed March 6, 1916. Serial No. 82,281.

To all whom it may concern:

Be it known that I, ALONZO E. RHOADES, a citizen of the United States, residing at Hopedale, county of Worcester, and State of Massachusetts, have invented an Improvement in Feeler-Motions For Looms, of which the following description, in connection with the accompanying drawings, is a specification, like characters on the drawings representing like parts.

The invention to be hereinafter described relates to filling replenishing controlling means for looms, and more particularly to the feeler motion for effecting filling replenishment prior to the complete exhaustion of the filling in the active shuttle.

The amount of filling remaining on the bobbin after a replenishing operation constitutes waste, and in addition to the loss of yarn value, entails labor and expense in removing the waste from the bobbin, which must be done before the bobbin can be again used. The amount of yarn remaining on the bobbin when it is ejected from the loom should be as small as possible consistent with proper weaving conditions and the formation of full picks up to the time of filling replenishment. This amount will depend directly upon the feeler motion which should detect approaching exhaustion of filling and then call for replenishment only when the desired degree of exhaustion has been reached.

One of the important features of the present invention, therefore, consists of a feeler guard which, so long as a working supply of filling is present in the shuttle on a detecting beat of the lay, engages the mass of filling and is held in feeler guarding position, thereby to prevent functional operation of the feeler, but when the filling has been drawn from the shuttle so that it is nearing exhaustion, the feeler guard is moved by the forward push of the bobbin from guarding position, thereby permitting the feeler to detect the condition of the filling and become functionally operative to effect replenishment when the desired degree of filling exhaustion has been reached and is detected.

In carrying this feature of the invention into practical effect, the feeler guard is preferably formed as a lever having an offset pivotal connection with a part of the feeler

and a filling engaging end portion which normally projects beyond or rearward of the filling engaging end of the feeler itself, so that upon a detecting beat of the lay if a working supply of filling is present in the shuttle, the feeler guard will engage the filling and be held thereby from pivotal movement due to the frontward beat of the lay, but when the filling is nearing exhaustion the small amount engaged by the feeler guard will be insufficient to hold it from pivotal movement under the frontward push of the bobbin, and it will be moved from guarding position and expose the feeler to perform its detecting function. When the feeler guard has been thus moved from guarding position by the frontward push of the bobbin and the filling has been replenished, it must be returned to guarding position, and another feature of the invention consists in the means for resetting or returning the feeler guard to guarding position after it has been moved from said position by the frontward push of the bobbin.

The above features and others forming part of the present invention will be hereinafter described in connection with the accompanying drawing showing one good practical form thereof, it being understood that changes may be made in the described construction without departing from the true scope of the invention as defined by the claims.

In the drawings:—

Figure 1 is a perspective view showing a feeler motion embodying the present invention, some of the parts being broken away and only so much of the loom being shown as is necessary to make clear the construction and operation of the invention;

Fig. 2 is a plan view of the feeler and associated parts on a somewhat smaller scale than in Fig. 1;

Fig. 3 is a detached detail perspective with portions broken away to show the relation of the parts when the lay beats up with a working supply of filling in the shuttle; and

Fig. 4 is a view similar to that of Fig. 3 when the filling is substantially exhausted and the feeler guard has been moved by the forward push of the bobbin to permit the feeler to perform its feeling function.

In the illustrated form of the invention, the feeler is of the penetrating and imping-

ing type, that is, it comprises two members, one of which is adapted to penetrate the filling in the shuttle on a detecting beat, or enter between the coils thereof, and the other is an impinging member adapted to contact with but not penetrate or sink into the filling on a detecting beat of the lay, and while the feeler guard of the present invention is especially useful in connection with this general type of feeler, it is not restricted thereto but may be advantageously employed with other forms of feelers.

The feeler stand 1 may be secured in position by any appropriate means, one good practical form of which comprises a bracket 2 to which the feeler stand is connected adjustably by the screws 3 which pass through a slot 4 in the stand. To further secure the stand to the bracket and yet permit of the desired relative adjustment, the bracket 2 is provided with the spaced adjusting screws 5, Figs. 1 and 2, the ends of which bear against the side of the stand 1. These details may of course be varied or replaced by any means for holding or supporting the feeler to be described in operative position.

The feeler stand is provided with a feeler, the function of which is to feel into the shuttle to detect the condition of the filling therein and upon substantial exhaustion of the filling to set parts in position to effect filling replenishment or otherwise change the condition of the loom.

In the present instance, the feeler stand has mounted thereon for movement toward and from the front of the loom, the feeler slide 6 which constitutes one form of feeler carrier, the shank portion 7 of which extends through the feeler stand, and means are provided for normally holding the feeler slide in its rearward position, such means in the present instance, comprising a spring 8, one portion of which bears against a shoulder 9, Fig. 2, of the feeler slide, and the other end of which is seated against the wall 10 of a cavity in the feeler stand in which the spring is contained, the construction being such that the spring 8 normally holds the feeler slide in its rearward position but permits such slide to move forward.

Rising from the feeler stand 1 is the bridge or abutment 11 having an opening 12. Extending upward from the feeler slide 6 in the front of the bridge 11 is a projection 13, between which and the front face of the bridge 11 extends the controller 14 which may be of usual type for controlling filling replenishment or other operation of the loom. In order that the controller 14 and projection 13 may be desirably held in associated relation, there extends through the projection 13 an adjusting screw 15 which may be provided with a usual lock nut for maintaining the rear face of the adjusting

screw in proper relation with the front face 65 of the controller 14.

The controller 14 as indicated more clearly in Fig. 1, extends to one side of the feeler stand and is pivotally mounted/upon a stud 16 connected to a transmitter 17 pivoted at 70 18 to a convenient part of the loom frame or a bracket extending therefrom, said controller, transmitter and pivotal connection of said parts being of the usual or any preferred construction, as well understood 75 by those skilled in the art. A spring 19 acting upon the controller 14 normally holds the end of the controller 14 against the front face of the bridge 11. As usual in this type of mechanism, the transmitter is provided with a side projecting portion 20, Fig. 1, having a slot through which the controller extends, the lower wall 21 of said slot being provided with the usual cam portion or incline, the construction being such that should 80 the controller 14 be moved toward the open portion of the slot, that is, to the right in Fig. 1, the adjacent end of the transmitter will be depressed and its other end operated to set certain parts not herein illustrated, as 90 they are well known to those skilled in the art, for initiating filling replenishment.

In order that the movement of the controller 14 may be properly guided, the bridge 11 has secured thereto a plate or guide 22. 95 This guide has an open or slotted portion 23, best indicated in Fig. 4, for properly guiding the end of the controller 14 as the latter is moved upon call for filling replenishment, as will be hereinafter more fully described. 100 Any suitable means may be employed for securing the controller guide 22 in operative position, as for instance, the screw bolt 24, Fig. 2. From the construction thus far described, it will be apparent that upon movement of the controller 14 for initiating filling replenishment, or toward the front of the loom in the present instance, it will ride along the cam portion 21 of the transmitter and will be guided in its movement by the 110 guide 22 which, as the controller returns to its initial position as will more fully appear, serves to direct the controller and accurately locate the operating end thereof. The guide 22 is of importance in this character 115 of construction, because it prevents movement of the controller by the cam part 21 of the transmitter and compels the transmitter to respond to movement under co-operation of the controller and the cam 21. 120

The feeler slide 6 is extended rearwardly and has an impinging end portion 25 which, under conditions to be hereinafter described, may contact with the filling in the shuttle as the lay makes its detecting beat. Rising 125 from the feeler slide 6 are the webs 26 between which at 27 is pivotally mounted the arm 28 which, for convenience of identifica-

tion, may be herein termed the actuator. Extending back from the pivotal point 27 of the actuator 28, is a projection 29 beneath which is a spring 30 normally acting to press the projection 29 upwardly and consequently to depress the bifurcated end 31 of the actuator into its lower or inoperative position with respect to the controller 14, substantially as indicated in Fig. 3.

10 Mounted to slide longitudinally of the feeler slide 6 is the penetrating member 32 of the feeler, the end portion 33 of which is preferably formed as a small projection adapted, under certain conditions, to sink 15 into or penetrate the filling in the shuttle as the lay beats up. The penetrating member 32 extends longitudinally of the feeler slide 6 and abuts at its front portion against a shoulder 34 below the pivotal mounting 20 of the actuator 28, the construction being such that should the penetrating member of the feeler be moved relatively to the impinging member 25, it will act against the shoulder 34 and lift the bifurcated end 31 25 of the actuator into position for engagement with the end of the controller 14, substantially as indicated in Fig. 4.

The relation of the impinging and penetrating members of the feeler is such that 30 when sufficient filling remains in the shuttle to enable the penetrating member to sink thereinto, before the impinging member engages the filling, said feeler members will be moved frontwardly on a detecting beat 35 of the lay, substantially in unison, and the actuator 28 will remain with its bifurcated end 31 in depressed position, as indicated in Fig. 3; but should the filling have reached substantial exhaustion and only sufficient re- 40 main in the shuttle to make one, two, or more picks, the penetrating member 33 will be struck by the more dense surface of the filling carrier or bobbin 35 as the lay beats up, and cause said penetrating member to 45 be moved relatively to the impinging member, thereby lifting the bifurcated end of the actuator 28 into operative relation with the controller 14, and upon further front- 50 ward movement of the lay, both members of the feeler and actuator 28 will be moved frontward to thereby correspondingly move the controller and initiate filling replenishment.

The present invention contemplates as an 55 important feature thereof, that when a working supply of filling is present, the feeler shall not engage the filling on the detecting beat, and shall only become functionally operative to detect the condition of 60 the filling in the shuttle when the filling has approached close to the condition of substantial exhaustion. To this end, a feeler guard is provided, the end of which normally projects beyond or rearward of the

feeler to engage the filling on the detecting beat and when a working supply is present in the shuttle, to be maintained in feeler-guarding position by the filling as the lay beats up; but when the filling has approached a condition when feeler action is 70 desired, the guard will be moved away from feeler-guarding position by the push of the bobbin against the feeler guard as the lay makes its detecting beat, thereby exposing 75 the feeler for its functional operation.

In the present instance, the feeler guard 36 is pivotally mounted at 37 on a lug 38 extending from one side of the feeler slide and its filling engaging end is roughened or formed with teeth 39, the construction being 80 such that when the lay makes a detecting beat and a working supply of filling is present, as indicated in Fig. 3, the roughened or toothed end 39 of the feeler guard will sink into the filling and prevent movement of 85 the feeler guard from guarding position as the lay continues its frontward movement. When, however, the filling approaches close to substantial exhaustion, and it is desired that the feeler shall become functionally 90 operative, the toothed or roughened end 39 of the feeler guard will engage the few coils of filling yet remaining on the bobbin or carrier in the shuttle or the more dense surface of the bobbin itself, and be moved side- 95 wise from its guarding position by the push or frontward movement of the bobbin as the lay advances, thereby exposing the feeler for its functional action. After the feeler guard has been thus moved from the guarding position and the feeler is permitted to act, the normal operation of the loom may continue until the feeler has detected that condition of filling exhaustion which calls for filling replenishment, whereupon, the 100 parts will be positioned as hereinbefore described to initiate filling replenishment.

In order to guide the feeler guard in its movement longitudinally of the shuttle to expose the feeler when the filling has approached a condition nearing exhaustion, the feeler guard is mounted for movement transversely of the feeler between the top surface of the feeler and a rearwardly-extending guide 40 secured to or formed as part of 110 the portions 26 mounted on the feeler slide.

When the feeler guard has been moved longitudinally of the shuttle from its guarding position as indicated in Fig. 4, due to the forward push of the bobbin or filling carrier in the shuttle and the lay retreats, it is desirable that the feeler guard be again returned to its feeler-guarding position, and to this end the feeler guard is provided with a projecting portion 41, adapted to engage the downturned end 42 of a rod 43 which may be suitably supported by the feeler stand. In the present instance the

rod 43 extends through suitable guides 44 of the feeler stand and is normally pressed rearwardly into operative position by a spring 45 disposed between the front guide 5 44 and an abutment or pin 46 secured to the rod 43, substantially as indicated in Figs. 1 and 2, the construction being such that should the feeler guard be moved into position as indicated in Fig. 4 on the forward 10 movement of the lay, it will be returned to its guarding position as the lay retreats, by engagement of the projection 41 extending from the feeler-guard-engaging end 42 of the rod 43. Other appropriate means 15 might, of course, be employed for returning the feeler guard to guarding position, but that described is found to be a good, practical form of means to this end.

In order that when the feeler guard is returned to guarding position it may be prevented from overmovement, a stop pin 47 may be employed, such stop pin preferably projecting upwardly from the feeler slide 6 as indicated in Figs. 1 and 2, and serving 20 to limit the resetting movement of the feeler guard.

What is claimed is:—

1. In a feeler motion for looms, the combination of a feeler to feel for the filling in 30 the shuttle and upon substantial exhaustion of the filling to initiate filling replenishment, and a feeler guard held in guarding position by engagement with the filling to prevent engagement of the feeler with the 35 filling on a detecting beat until the filling nears substantially exhaustion and to be moved from feeler guarding position by the frontward push of the bobbin when the filling approaches substantial exhaustion to 40 permit the feeler to detect the condition of the filling.

2. In a feeler motion for looms, the combination of a feeler to feel for the filling in the shuttle, means controlled through the 45 feeler to initiate filling replenishment when the filling is substantially exhausted, and a feeler guard adapted to be held in feeler guarding position by the frontward push of the filling when a working supply is in 50 the shuttle and movable from said position by the frontward push of the bobbin when the filling approaches substantial exhaustion.

3. In a feeler motion for looms, the combination of a feeler, a feeler guard normally extending beyond the end of the feeler and having a movement with and independent of the feeler, said guard having a portion to hold the guard from movement independent of the feeler by engagement with 55 the filling when a working supply is present and permitting said feeler guard to move independent of the feeler out of guarding relation thereto when the filling is substantially exhausted.

4. In a feeler motion for looms, the combination of a feeler carrier, a feeler carried by the feeler carrier to feel for the filling in the shuttle, and a feeler guard mounted on the feeler carrier for movement with and independently of the 70 carrier, said feeler guard having a roughened end portion to engage the filling in the shuttle and be held from such independent movement by the filling when a working supply is present and be moved independently of the carrier when the filling approaches substantial exhaustion. 75

5. In a feeler motion for looms, the combination of a feeler slide, a feeler, and a feeler guard, means acting upon the guard 80 to hold it in guarding position between detecting beats of the lay, and said feeler guard having a portion to engage the filling and be held in guarding position by engagement with the filling as the lay makes its detecting 85 beat with a working supply of filling present in the shuttle and to be moved from guarding position on a detecting beat when the filling nears substantial exhaustion.

6. In a feeler motion for looms, the combination of a feeler slide carrying a feeler to feel for the filling in the shuttle, a feeler guard pivotally mounted and having a roughened or toothed end portion to engage the filling in the shuttle on a detecting beat, 95 and to be moved about its pivot from guarding relation with the feeler by the push of the bobbin when the filling has approached a condition near substantial exhaustion to 100 permit the feeler to detect the further condition of the filling.

7. In a feeler motion for looms, the combination of a feeler comprising an impinging and a penetrating member, a feeler guard having a filling engaging end normally projected beyond the ends of said feeler members to engage and be held by the filling in 110 guarding position when a working supply is present on a detecting beat and to be moved from guarding position by the frontward push thereon when the filling approaches substantial exhaustion, and means for returning the feeler guard to guarding position. 105

8. A feeler motion, comprising in combination a feeler to detect the condition of the filling in the shuttle, a feeler guard to prevent detecting action of the feeler until the filling approaches a condition near to substantial exhaustion and to then be moved in a direction longitudinally of the shuttle 115 out of guarding position, and means for initiating filling replenishment when the feeler detects substantial exhaustion of the filling in the shuttle. 120

9. A feeler motion, comprising in combination, a feeler to detect the condition of the filling in the shuttle, a feeler guard to prevent detecting action of the feeler until 125

- the filling approaches a condition near to substantial exhaustion and to then be moved in a direction longitudinally of the shuttle out of guarding position, means for moving 5 the feeler guard longitudinally of the shuttle in the opposite direction, and means for initiating filling replenishment when the feeler detects substantial exhaustion of the filling in the shuttle.
10. In a feeler motion for looms, the combination of a feeler to feel for the filling in the shuttle and movable toward and from the front of the loom, a feeler guard projecting beyond the end of the feeler to engage 15 the filling and be held in guarding position by the filling as the lay beats up until the filling is near to substantial exhaustion and to be then moved longitudinally of the shuttle away from guarding position, 20 and yielding means for returning the feeler guard to guarding position as the lay moves back.
11. In a feeler motion, the combination of a feeler slide carrying a feeler to feel for the filling in the shuttle, a feeler guard having an offset pivotal connection with the feeler slide and provided with a filling engaging end projecting beyond the end of the feeler to be engaged and held by the filling 25 in guarding position as the lay beats up and to be moved in a direction longitudinally of the shuttle by the frontward push when the filling nears substantial exhaustion, and means for initiating filling replenishment when the feeler detects substantial exhaustion of filling.
12. A feeler motion, comprising a feeler to feel for the filling in the shuttle, a slide carrying said feeler, a feeler guard having 30 an offset pivotal connection with the slide, that the guard may be moved about its pivot from guarding position by the frontward push of the filling carrier or bobbin, and
- feeler guard resetting means to turn the feeler guard to guarding position on the 45 feeler slide by rearward movement of the slide.
13. A feeler motion for looms, comprising, in combination, a feeler to detect the condition of the filling in the shuttle, a 50 feeler guard to prevent detecting action of the feeler until the filling in the shuttle approaches a condition near to substantial exhaustion and to then be moved out of guarding position to permit detecting action by 55 the feeler, and means for initiating filling replenishment when the feeler detects substantial exhaustion of the filling in the shuttle.
14. A feeler motion for looms, comprising, in combination, a feeler to feel for the filling in the shuttle, and upon substantial exhaustion of the filling to initiate filling replenishment, a carrier for normally holding the feeler in rearward position, and a 60 feeler guard to prevent engagement of the feeler with the filling on a detecting beat until the filling approaches a condition of substantial exhaustion and to then be moved to one side from feeler guarding position to 70 permit the feeler to detect the condition of the filling.
15. In a feeler motion for looms, the combination of a feeler to feel for the filling in the shuttle and upon substantial exhaustion 75 of filling to initiate filling replenishment, a feeler guard mounted for movement laterally with respect to the feeler and having an end to engage and be held by the filling from such lateral movement until the filling 80 nears substantial exhaustion and then moved laterally to permit the feeler to detect the condition of the filling.

In testimony whereof I have signed my name to this specification.

ALONZO E. RHOADES.
